(57) **CLAIM**

We claim the ornamental design for a non-return device valve support support member, as shown and described.

DESCRIPTION

FIG. 1 is a perspective view of a non-return device valve support member showing our new design.

FIG. 2 is a top plan view of the non-return device valve support member shown in FIG. 1.

FIG. 3 is a bottom plan view of the non-return device valve support member shown in FIG. 1.

FIG. 4 is a right side view of the on-return device valve support member shown in FIG. 1.

FIG. 5 is a left side view of the non-return device valve support member shown in FIG. 1.

FIG. 6 is a front elevational view of the non-return device valve support member shown in FIG. 1; and,

FIG. 7 is a rear elevational view of the non-return device valve support member shown in FIG. 1.
